GEORGE W. MILLS, JR., OF NEW YORK, N. Y., ASSIGNOR TO WILLIAM A. KEYS, OF NEW YORK, N. Y.

NECKWEAR.

1,109,858.

Specification of Letters Patent.

Patented Sept. 8, 1914.

Application filed July 17, 1912. Serial No. 709,849.

To all whom it may concern:

Be it known that I, GEORGE W. MILLS, Jr., a citizen of the United States; and a resident of the city of New York, county of 5 Kings, and State of New York, have invented certain new and useful Improvements in Neckwear, of which the following is a specification.

My invention relates to neckwear, and 10 particularly to that type of neckwear which is formed into a knot by the wearer.

In two-ply collars, particularly the high-band type—that is a collar in which the band of the collar and the outer fold of the 15 material come very close together, especially at the back so as to leave very little tie space, the tendency is to grip the tie and prevent its easy adjustment when being tied. It has also been found that the seam in the 20 center of the neckband tends to catch on to the collar button thus retarding adjustment, and frequently destroying the scarf.

It is to overcome these objections, without defacing the scarf, without additional expense, and at the same time to make a scarf 25 of the folded type, thinner in the neckband but stronger, that my invention relates.

The type of scarf to which my invention especially relates is known as the folded 30 scarf—that is a scarf having the same material throughout on both the inner and outer faces, folded so as to come together in the back of the scarf. In the construction of such scarfs heretofore they have been provided with a seam in the center of the neckband. It is this seam which tends to catch 35 on the collar button. This seam also makes the scarf thicker in the center of the neckband. It has also been found that in making 40 scarfs cut on the bias, that the material being cut on the bias will stretch and the scarf very soon becomes mutilated or shapeless. This latter objection I have also overcome in my improved scarf.

45 In the drawing forming a part hereof Figure 1 shows the inner side of the scarf; Fig. 2 shows the outer face of the scarf; Fig. 3 shows the inner face of the scarf with a portion unfolded so as to show the construction; and Figs. 4, 5 and 6 show details of the construction.

In the drawings in which similar numerals refer to similar parts, 1 is the material of the neck-tie proper, as shown, the material being cut on the bias. In ties cut on

a bias for economy of manufacture the material is cut in two pieces and joined as shown in the drawings at 11. My invention is equally applicable to a scarf cut on the straight.

60

2 represents the interlining of the tying ends. This is preferably of a soft loosely-woven fabric, such as canton flannel. As shown in Fig. 3 the interlining 2 is fully exposed in one of the tying ends, and there 65 is a similar interlining in the other tying end in Fig. 3, which is shown in dotted lines. The interlinings 2 of the tying ends are secured to an interlining or reinforcing strip 3 of a thin and comparatively strong fabric 70 extending preferably throughout substantially the length of the scarf. While I prefer to have the thin interlining or reinforcing strip extend substantially throughout the length of the scarf, especially in a bias-cut scarf, it is not essential that it should extend beyond the point where it engages with the interlining of the tying ends. This thin interlining or reinforcing strip 3 is cut on the straight, and may be of tape with a 75 selvage edge or of strips of muslin or similar material. The strip 3 when used as hereafter described serves as a reinforcing piece to reinforce the material 1 of the necktie proper. The interlinings 2 of the tying ends 80 are secured to the interlining or reinforcing strip 3 by suitable stitching 4, either at the end of the neckband or within the neckband. If desired in some scarfs, for instance those cut on the straight, the interlining in the 85 neckband may be dispensed with, thereby making the neckband thinner, and the interlinings of the tying ends held in place by stitching.

I cut the scarf so that when it is folded as 90 shown in Fig. 1, the edges of the material will meet and overlap intermediate the edges of the tying ends, where I prefer to attach them together by a seam 5. The point of meeting of the edges of the material of the 100 scarf in the tying ends is intermediate the edges of the tying ends, and near the end of the neckband or at points intermediate the ends of the neckband. The meeting place of the edges of the material then passes to 105 the right or left of the center of the neckband, preferably at an acute angle as shown in Fig. 1 at 6 to the edge of the neckband as shown at 7. The advantage of this is that the tying ends of the scarf have all the 110

features of the ordinary folded scarf, and the neckband has the advantage of having only two ply of scarf material through a part of it, or all of it, thus making it substantially thinner than it would otherwise be where the seam extends through the center of the neckband, and at the same time dispenses with the seam in the center of the neckband. By using the thin interlining or reinforcing strip 3 in the neckband I am also enabled to make the scarf thinner at that point. If a scarf is cut on the straight it is not essential to use any interlining in the neckband whatever as the material of the scarf proper being on the straight affords sufficient strength to the neckband. After the scarf has been assembled as shown in Figs. 1 and 2, and particularly in a scarf cut on the bias, I add the stitching 8 which extends along each side of the neckband, and then at its ends across the neckband either straight or at an angle as shown in Figs. 1 and 2. I have omitted it in Fig. 3. This stitching I preferably arrange very close to the edge of the scarf so that it will penetrate both the inner and outer faces of the scarf material proper, and at the same time pass through the thin interlining or reinforcing strip at the sides of the neckband, if an interlining or reinforcing strip is used, and at the ends pass through not only the material of the scarf proper, but also the thin interlining or reinforcing strip, and in addition the interlinings 2 of the tying ends. This stitching 8 may, if desired, penetrate only the interlining and the inner face of the material of the scarf. Where the edges of the material of the scarf meet on the inner face, I attach the material together by blind stitching—that is stitching which is not visible on the outer side of the inner face of the scarf, as shown in Figs. 4 and 5, where the stitching 9 engages with the two plies of the material of the scarf proper on the inner face, and also with the thin interlining or reinforcing strip 3, and with the heavier interlining 2. This adds considerable strength to the scarf, particularly when cut on the bias, by reason of the fact that the stitching penetrates the bias material, and also the thin interlining or reinforcing strip 3 which passes through the length of the scarf. As thus constructed, the strip 3 serves as a reinforcing strip to reinforce the material of the necktie proper. The result is that when in tying the knot or bow a person pulls at either end of the scarf to adjust it he clasps not only the material of the scarf proper, but also the thin interlining or reinforcing strip 3 which is stitched to the material of the scarf proper, and as he pulls it tends to hold the scarf material proper in form without stretching as the strain is carried by the thin interlining or reinforcing strip. Where the material of the scarf meets

on the edge of the neckband, I sometimes sew it together with stitches which are so located that they engage the parts folded in as shown in Fig. 6. I have also found that by cementing the inner face of the material of the scarf to the interlining the inner face may be made smoother and in Fig. 6, I have shown a cross section of the neckband in which 10 represents the cement which, as shown, holds the inner ply and the interlining together. If desired the stitching 8 may be omitted, when the neckband is cemented as shown in Fig. 6, although I prefer to use it in a bias scarf. The cementing of the neckband may be omitted if desired as it is not essential.

The completed scarf as shown in Figs. 1 and 2 embodying my invention may be made without any increased expense and has all of the advantages of the ordinary folded scarf having the same material throughout on its inner and outer faces, with the addition that it has no seam on the inner face of the neckband, it is considerably stronger than the ordinary scarf, although thinner in an intermediate portion, particularly when cut on the bias, it facilitates adjustment in two-fold collars, and may be used on either a two-ply collar or the ordinary standing collar as no part of the scarf is defaced in order to provide the adjusting features, and increased strength. The scarf is made on both its inner and outer surface of the same material and is artistic and slightly when exhibited in shops for sale.

Modifications could be made, such for instance as constructing a scarf as shown in Figs. 1, 2 and 3, using an interlining of the same thickness throughout, although when so constructed the neckband would be only a trifle thinner than when constructed in the ordinary way with the seam running through the center of the scarf, without departing from the spirit of my invention. The length of the intermediate portion of the scarf where the material meets substantially on the edge may be equal to the length of the neckband or somewhat shorter, if desired, but I prefer that it should not extend beyond the point where the scarf begins to increase in width.

What I claim is:—

1. In a necktie, a neckband and two tying ends formed of a fabric cut and folded so that the inner and outer faces are of the same fabric throughout, in the tying ends the adjacent edges of said folded fabric meeting on the inner face of the necktie intermediate the edges thereof, and in an intermediate portion of the necktie the edges of the said folded fabric meeting substantially on one edge only thereof.

2. In a necktie having a neckband and two tying ends formed of fabric cut from piece goods, and folded so that the inner and

outer faces are of the same fabric through-
out, in the tying ends the adjacent edges of
said folded fabric meeting on the inner face
of the necktie intermediate the edges there-
of and in an intermediate part of the neck-
tie the adjacent edges of said folded fabric
meeting substantially on the edge thereof,
a thin narrow interlining extending
throughout said necktie and supplemental
10 interlinings in the tying ends substantially
wider in part than said thin interlining.

3. In a necktie having a neckband and
two tying ends, the two faces of which are
of the same fabric formed by cutting mate-
rial from piece goods and folding same to
15 form said neckband and tying ends, the
edges of said folded fabric in the tying ends
meeting on the inner face of the necktie in-
termediate the edges thereof, and in an in-
20 termediate part of the necktie the edges of
said fabric meeting on one edge only, and
an interlining in said necktie, an intermedi-
ate portion of the fabric of the inner face
only of the necktie being cemented to the
25 interlining.

4. A necktie formed of suitable fabric
folded and shaped in a flat tubular form,
embodying a narrow neckband portion and
tying-end portions at the ends of the neck-
30 band portion, the edges of the back fold
of the folded fabric in the tying ends being
intermediate the edges of the tie, an inter-
lining in the tying-end portions, and stitches
in the tying-end portions attaching the in-
35 terlining to the back fold only of the tie
throughout the tying ends of the tie where-
by said stitches will not appear on the outer
face of the tie.

5. In a necktie having a neckband and
40 two tying ends formed of a fabric material
cut and folded to form the face and back
of said necktie, the edges of said material
meeting on the back of the tie intermediate
the edges of the tying ends and a reinforce-
45 ing strip extending substantially through-

out the length of said necktie and secured to
the fabric of the back only of the tying ends
of said necktie.

6. A necktie formed of a folded fabric
and comprising a narrow neckband portion, 50
knot-forming portions at the end of the
neckband portion and enlarged ends, the
edges of the folded fabric forming a longi-
tudinal seam at the back of the tying ends
of the necktie in combination with a longi-
55 tudinally extending, relatively strong, in-
elastic flexible reinforcing strip reinforcing
the back of the scarf throughout the neck-
band and a substantial portion of the tying
ends thereof, longitudinal stitching connect-
60 ing said reinforcing strip to the back fold
only of the said folded fabric throughout
the said knot forming portions, and lines of
stitching connecting said reinforcing strip
to back and face folds of the tie throughout
65 the neckband portion thereof.

7. A necktie formed of suitable fabric
folded and shaped in a flat tubular form,
embodying a narrow neckband portion and
wider tying-end portions at the end of the 70
neckband portion, the edges of the back fold
of the folded fabric in the tying ends being
intermediate the edges of the tying ends of
the tie, an interlining in said tying-end por-
tions, a reinforcing strip extending through-
75 out the neckband and the tying-end por-
tions, said strip being substantially equal in
width to the neckband portion, and stitches
attaching the interlining of the tying ends,
to the back fold only, of the said folded 80
fabric throughout the tying-end portions, so
arranged that said stitches will not appear
on the outer face of the tie.

In testimony whereof, I have signed my
name to this specification, in the presence of
two subscribing witnesses.
